STEAM PLANT

Original application filed August 15, 1928, Serial No. 299,801, and in Germany June 27, 1928. Divided
and this application filed January 4, 1930. Serial No. 418,511.

In plants of this character, especially in cases where high steam pressures and temperatures are employed, the feed water purity for the high pressure steam generator is by far more important, especially in cases of purely tubular steam generators, than it was heretofore with the ordinary low pressure and low temperature drum boiler, because in tubular boilers the impurities are more likely to impair the efficiency and correct operation of the boiler. These conditions have suggested to the art the division of the steam generation for the high and low pressure sections of the prime mover into two distinct stages, so that the steam discharged from the high pressure prime mover is not directly delivered into the low pressure section or sections of the prime mover system, from which latter the condensate might be returned to the steam generator in impure condition. Between the high and low pressure sections of the prime mover system is then interposed a steam transformer in which the temperature of the high pressure steam discharged from the high pressure prime mover is utilized for generating low pressure steam for the low pressure section of the prime mover system which latter constitutes thereby an entirely independent medium circulating system. This avoids the contamination of the high pressure steam generator water by the low pressure steam consumers, and permits the return of the high pressure steam condensate directly to the high pressure steam generator. The thermodynamic losses which are suffered in a system of this character are by far outweighed by the great advantages gained in the pureness of the feed water for the high pressure system, and besides by the judicious employment of mixing condensers in the low pressure steam system, instead of surface condensers, thermal losses suffered in the high pressure system are practically retrieved in the low pressure system. This is true, because in mixing condensers the efficiency and the vacuum are greater than in surface condensers, and in addition the first cost and maintenance cost of a mixing condenser which contains

only simple sprays, are both considerably lower than those of surface condensers.

A steam generating plant of this character and involving the above-mentioned general ideas is disclosed in my copending application, Serial No. 299,801, filed August 15, 1928, of which the present application is a division.

This present application deals with some particular improvements on this character of plant, based on the following consideration. The interposition of a steam transformer or heat exchanger alone between the high pressure and low pressure sections of the prime mover system, such as is suggested in the aforementioned parent application, does not complete the measures necessary for efficiently solving the feed water problem for high pressure and high temperature steam generators. In particular with the use of purely tubular steam generators, it must be taken into account that the feed water contains dissolved minerals which are apt to crystallize during the steam generation, and the steam is apt to carry these crystals along and deposit them in the generator tubes where their accumulation is likely to dangerously reduce the cross-section of the tubes, and in some cases is apt to clog them altogether. Such crystals are also likely to cause considerable wear of the turbine buckets.

The above disadvantages are overcome according to the present invention by interposing into the high pressure circulating system, and directly ahead of the steam transformer, a steam purifier, which constitutes a purifying chamber filled with a suitable washing liquid, and in which the steam exhausted from the high pressure prime mover is condensed and regenerated on the surface of the liquid before it enters the steam heat exchanger. This washing process dissolves the crystallized mineral matter which might be contained in the steam, so that it can be drained off from the washing chamber, and thereby removed from circulation system.

If reciprocating prime movers are used in the high pressure section of the prime mover system, besides a mechanical or chemical

purifier may be interposed ahead of the steam purifier in which the oil carried along by the steam is removed.

My invention is illustrated diagrammatically in the accompanying drawing which diagrammatically represents the lay out of a steam generating system according to my invention.

Referring to the drawing, 1 represents the high pressure high temperature steam generator which delivers by way of a steam main 3 steam to the prime mover 4 which, in this case, has the form of a reciprocating piston machine. The steam is discharged from the low pressure stage 76 of prime mover 4, and after passing through an oil separator 78 is discharged through a conduit 84 into a steam washing device 82 of the steam regeneration type. This device functions by condensing the steam supplied to it in the washing liquid, and by regenerating it on the surface of the liquid. The steam thus regenerated is free from all impurities, including mineral salts, which the generator steam might have carried along, and which remain dissolved in the washing liquid. As a washing liquid the same kind of liquid is used as the one from which the vapor is generated in the high pressure system; in the present case of high pressure steam generation, water would be used as a washing liquid. Water as a steam washing liquid is well known in the art. The purified steam passes from this washing chamber by way of a conduit 85 into the steam heat exchanger or steam transformer 83 in which the heat exchanger 12 is disposed through which the high pressure high temperature exhaust steam passes, and which heats the water contained in the steam transformer, thereby generating low pressure steam.

Preferrably the steam washing chamber is made a part of the steam transformer by dividing the transformer drum by means of a partition wall 81 into two compartments, one of which forms the steam washing chamber, and the other the steam transformer chamber.

The water from which the low pressure steam is generated in the steam transformer is supplied from a sump 13 through a pump 14, and by way of feed water heaters 25, 45 into the steam transformer, and the secondary steam generated in the steam transformer is supplied by way of secondary main 21 to a low pressure steam consumer which is in this case represented by a low pressure turbine 48. The exhaust steam from this turbine is condensed in a mixing condenser 52 which is supplied with cold water through pump 53, the condensate from this condenser flowing by way of discharge pipe 54 into the sump 13.

The condensate discharged by the heat exchanger 12 of the steam transformer flows

through the pipe 17 into the feed water heater 25 aforementioned, and thence through pipe 26 into the sump 18 from which it is delivered by feed pump 19 into the high pressure steam generator 1, thereby establishing an entirely separate circulation independent of the low pressure steam generating circuit.

Aside from heating the feed water for the steam transformer by means of the condensate discharged from the heat exchanger 12, this feed water is further heated to a suitable higher temperature by means of interstage steam tapped between the stages 75 and 76 of the high pressure prime mover 4, which after passing through an oil separator 86 first serves for superheating the secondary steam generated in the steam transformer through a coil 42 disposed in the dome 68 of the steam transformer. From coil 42 the steam passes through pipe 24 into the feed water heater 45, whence it is discharged through a pipe 87 by way of a control valve 88 into the steam washing chamber. A check valve 100 is provided near the steam entrance into the washing chamber, in order to prevent the washing liquid from entering feed water heater 45 in case the pressure in the washing chamber exceeds that in the water heater 45.

Aside from feeding the steam washing chamber with exhaust steam from prime mover 4, an additional supply of steam may be delivered directly from main 3 by way of a control valve 90 which is controlled by a pressure responsive device 92 connected to main 3 such that as the pressure in steam main 3 increases valve 90 opens further and delivers more steam into the steam washer and steam transformer.

For controlling the feed water supply to steam transformer 83, a valve 32 is provided in the feed water line between pump 14 and feed water heater 25, which valve is controlled by a pressure responsive device 34 responding to pressure variations in the secondary steam main 21, so that when the pressure in the latter decreases, more feed water is supplied to the transformer and when it increases, the reverse occurs.

Likewise, the pressure variations in secondary steam main 21 are utilized for controlling the fuel supply to steam generator 1 by means of pressure responsive device 38 connected to the secondary main and controlling fuel supply valve 104 such that when the secondary steam pressure decreases the fuel supply increases and when the pressure increases the fuel valve is actuated the reverse way.

I claim:

A high and low pressure vapor power plant having a high pressure circuit for the operating medium including a high pressure vapor generator, a high pressure prime mover supplied with vapor from the generator, a

vapor transformer of the indirect heating type connected at its primary side to the exhaust side of said high pressure prime mover, and means for returning the condensate from the primary side of the vapor transformer to said generator, the low pressure medium circuit including the secondary side of said vapor transformer and a low pressure vapor consumer, the high pressure medium circuit including a vapor washer of the direct vapor regeneration type containing a washing liquid of the same kind as the liquid from which the high pressure vapor is generated, said washer being interposed between said prime mover exhaust and the primary side of said transformer, whereby through the regeneration of vapor from said washing liquid purified vapor is delivered to said transformer and purified condensate 20 is returned to said generator.
